UNITED STATES PATENT OFFICE.

LILLIAN M. SAYEN, OF ROCK, MICHIGAN.

CHAIR.

1,167,846.

Specification of Letters Patent. Patented Jan. 11, 1916.

Application filed July 10, 1915. Serial No. 39,031.

To all whom it may concern:

Be it known that I, LILLIAN M. SAYEN, a citizen of the United States, residing at Rock P. O., in the county of Delta and State 5 of Michigan, have invented certain new and useful Improvements in Chairs, of which the following is a specification.

My invention relates to improvements in chairs, and has especial reference to chairs 10 for use in nurseries for children.

One of the objects of my invention is to combine, in a novel manner, a child's toilet chair with a stool, thereby jointly providing a high chair, and with a trundle platform, 15 and to thereby provide a vehicle to more conveniently move the chair and its occupant from place to place in the room.

Other, further and more specific objects of my invention will be readily understood 20 by persons skilled in the art, from a consideration of the following description when taken in conjunction with the drawings, wherein:—

Figure 1 is a side elevation, showing the 25 chair mounted on a nursery table and secured thereto by clamps engaging two opposite lower rungs. Fig. 2 is a section, taken on line 2—2 of Fig. 1. Fig. 3 is a section, taken on line 3—3 of Fig. 2. Fig. 4 is a side elevation of the chair secured in like manner to the trundle platform. Fig. 5 is a horizontal section on line 5—5 of Fig. 4.

In all the views the same reference characters are employed to indicate similar 30 parts.

My combined chair provides a novel and advantageous combinative arrangement with other mentioned appurtenances of the nursery.

The chair and table are each separately 35 useful articles and each contribute, when associated, to perform conjoint results, or in other words, the usefulness of the chair is promoted by the association of the table 40 and vice versa, and so with the trundle platform, the chair and platform when associated, jointly, provide a convenient go-cart or vehicle for indoor use.

A convenient, simple means for securely 45 connecting the parts together forms another feature of my invention.

My chair 10 is preferably provided with a pair of arms 11 and a tray 12, the latter is pivoted to one arm and secured in position 50 by means of a pin 13, which depends from the lower surface thereof and enters a prop-

erly disposed perforation in the other arm, to hold the tray in place and to prevent the child from moving from the chair. To move the tray 12 from its closed position on 55 the arms it is only necessary to lift it slightly at the end where the stud or pin 13 enters the chair arm 11 and then move it outwardly upon its hinge.

The chair is provided with two relatively 60 long, substantially vertically disposed legs and back parts 14 and 15 and two shorter front legs 16 and 17, the latter terminating at the perforate seat or bottom 18. Below the seat 18 is a cabinet 19, containing a 65 drawer 20. The drawer is provided with rounded corners so as to easily be cleansed and is slidable into and out of the cabinet between the front legs 16 and 17.

A closure, or cover 21, is hinged, as at 22, 70 to the bottom or seat 18 of the chair, and is adapted to close the perforation 22' in said bottom.

The legs 14, 15, 16 and 17 are joined near 75 their bottom ends with rungs 23—23 which are all, preferably, in substantially the same horizontal plane.

The nursery table 24 is provided with four 80 legs 25—25, as usual with tables, being joined together with the usual rungs 26—26 85 and provided with a top 27 substantially the same dimensions and shape as the top 27' of the trundle platform. The top 27, is of width sufficient to enter between the legs 15 and 17 on one side and the legs 14 90 and 16 on the other side, and to permit the front and rear rungs 23—23 to rest upon the top.

Clamps 28, pass through the tops 27, 27' and are provided with a turned over end 29 95 and screw threaded shank 30. The turned over ends overlie the rungs 23—23 of the chair, and when the butterfly nuts 30'—30' are properly turned, the chair is firmly held by the clamps to the table top 27 or the trundle top 27'. When the chair is taken from the table, the clamps 28—28 are turned so that their salient ends 29—29 rest upon the table, when the nuts 30'—30' may be further tightened which will hold the clamps 100 with their exposed ends in contact with the upper surface of the table and therefore they will be out of the way and danger to the child.

When the chair is separated from the 110 table, and the trundle platform, each of the articles may be separately and advanta-

geously used for the convenience and entertainment of the child, but when they are associated they jointly provide a new nursery article of furniture. The trundle platform comprises a platform 27', substantially the same size, dimension and configuration as the top of the table, and an underlying frame 33 provided with rollers or wheels 34.

Having described my invention, what I claim is:-

- 10 1. In combination with a chair, having four leg-joining rungs in the same horizontal plane, of a support having a top, within one pair of oppositely disposed rungs and projecting beyond the other pair, and clamps secured to the top and engaging the appropriate pair of rungs.
- 15 2. In combination with a chair having

four leg-joining rungs, in the same horizontal plane, of a support having a top, within one pair of oppositely disposed rungs and underlying and projecting beyond the other pair; a plurality of clamps, each comprising a screw-threaded shank and a turned over end to engage a given pair of rungs, 20 said shanks passing through said top and a nut on the threaded shank of each clamp, under said top, to cause the opposite pair of rungs to securely engage said top.

In testimony whereof I hereunto set my 25 hand in the presence of two subscribing witnesses.

Mrs. LILLIAN M. SAYEN.

In the presence of—
EVA RAYMOND,
FRANK JOHNSON.
